UNITED STATES PATENT OFFICE.

SILAS TUTTLE, JR., OF BROOKLYN, NEW YORK.

DESIGN FOR A HOT-AIR-REGISTER FRONT.

SPECIFICATION forming part of Design No. 17,639, dated August 16, 1897.

Application filed May 9, 1897. Serial No. 237,654. Term of patent 14 years.

To all whom it may concern:

Be it known that I, SILAS TUTTLE, Jr., a citizen of the United States, residing at Brooklyn, in the county of Kings and State of New York, have invented and produced a new and original Design for a Hot-Air-Register Front, of which the following is a specification, reference being made to the accompanying drawing, in which my newly-designed register-front is represented in front elevation or face view.

The marginal field of the design consists of the ornamental configuration of the open fret-work front, comprising the transverse bars *a*, joined to the ends of the border-frame by the circular devices *b*, and said transverse bars and the sides of the border-frame joined to the longitudinal and transverse bars *c* by the crosses *d*, with intervening studs, *e*.

The inner field of said design consists of the corner scrolls, *f*, bars *g*, connecting said scrolls, intermediate scrolls, *h*, sexangular figure *i*, with arrow-shaped terminals *k*, hour-glass-shaped figure of diagonal bars *j*, with top and bottom shapes and joining the corner scrolls, and the central ring, *m*, said scrolls, bars, arrow-heads, and ring being connected or intertwined, as represented in the print.

I claim—

1. The design for a register-front, comprising the devices of the marginal field—viz., the transverse bars *a*, joined to the ends of the border-frame by the circular devices *b*, and said transverse bars and the sides of the border-

frame joined to the longitudinal and transverse bars *c* by the crosses *d*, with intermediate studs, *e*, as herein set forth and shown.

2. The design for a register-front, comprising the devices of the inner field—viz., the corner scrolls, *f*, bars *g*, connecting said scrolls, intermediate scrolls, *h*, sexangular figure *i*, with arrow-shaped terminals *k*, hour-glass-shaped figure of bars *j*, with top and bottom shapes and joining the corner scrolls, and the central ring, *m*, said scrolls, bars, arrow-heads, and ring being connected or intertwined, all as herein set forth and shown.

3. The design for a register-front, comprising the hour-glass-shaped figure of diagonal cross-lines through the central portion of the figure, which join upon the corner scrolls, also said scrolls, scrolls *h*, and ring *m*, as herein set forth and shown.

4. The design for a register-front, comprising the sexagonal figure with arrow-head terminals, and the hour-glass-shaped figure of diagonal cross-lines through the central portion of the figure, as herein set forth and shown.

5. The design for a register-front, comprising the hour-glass-shaped figure of diagonal cross-lines which join the corner scrolls and the sexangular figure with arrow-head terminals, as herein set forth and shown.

SILAS TUTTLE, JR.
